JAMES L. RAY, OF SWARTHMORE, PENNSYLVANIA, ASSIGNOR TO WESTINGHOUSE ELECTRIC & MANUFACTURING COMPANY, A CORPORATION OF PENNSYLVANIA

FLUID PRESSURE GOVERNOR

Application filed June 15, 1928. Serial No. 285,673.

My invention relates to governors, more particularly to fluid-pressure governors for prime movers and it has for its object to provide a governor affording improved regulation. A specific object is to provide greater variations in the fluid pressure acting on the pressure-responsive element, in order to obtain greater movement of the governing valve in response to speed change.

10 In the design of fluid-pressure governors, difficulty has been experienced in providing sufficient deflection of the governor spring upon change in governing pressure resulting from a speed change. A spring which is sufficiently strong to oppose the governing pressure and at the same time give sufficient deflection is found to be inordinately long.

In accordance with my invention I provide a pressure transformer which provides 20 a fluid pressure varying inversely with the governing fluid pressure, and I apply such fluid pressure to the pressure-responsive element in opposition to the governing fluid pressure. Upon an increase in speed the governing fluid pressure increases, while the second fluid pressure decreases, thereby magnifying the effective pressure change on the pressure-responsive element and providing sufficient force to obtain an adequate spring 30 deflection.

I also provide, in accordance with my invention, a pressure transformer of simple and inexpensive design.

Apparatus exemplifying my invention is 35 illustrated in the accompanying drawings, in which:

Fig. 1 is a diagrammatic view of my governor as applied to a prime mover, with the parts thereof shown in section; and

40 Fig. 2 is a sectional view of a modified form of pressure transformer.

Referring to the drawings in detail, I show a turbine 10 having a steam chest 11 and a shaft 12. A pump is provided which includes a casing 13 and an impeller 14 mounted

directly on the shaft 12. The pump is supplied with fluid, preferably a liquid, such as lubricating oil from a reservoir 64 through a conduit 65, and provides a fluid pressure varying as the square of the speed of the 50 shaft 12, as is well known of centrifugal pumps. The pressure developed by the pump is transmitted through a conduit 15 to a pressure-transforming device 16.

The device 16 includes a casing 17 having 55 a partition 18 therein dividing the casing into two compartments 19 and 21. A bore portion 22 is formed in the partition 18, and loosely fitted in this bore portion is a piston portion 23 which is an integral extension of 60 a pressure-relief valve 24. A small passage 25 also extends through the partition 18 and is disposed in close proximity to the bore portion 22. An adjustable needle valve 26 provides a restricted orifice 27 in the passage 65 25. The conduit 15 communicates with the chamber 21 of the pressure transformer and supplies governing fluid pressure thereto, which pressure is effective on the lower end of the piston portion 23.

The passage 25 communicates with an annular groove 29 in the partition 18, said groove being concentric with the bore 22. The valve 24 has a flange 31, which seats on the partition 18 outwardly of the groove 29, 75 and which forms a recess 59 with the piston portion 23. The valve 24 is biased to closed position by a compression spring 32, interposed between the valve and a spring holding member 62. The position of the latter 80 may be adjusted by a screw 63 to vary the force exerted by the spring 32. A passage 33 is formed in the partition 18 and provides communication between the groove 29 and a conduit 34.

The conduit 15 communicates with a branch conduit 35, and the conduits 34 and 35 communicate with a relay valve casing 36 at opposite ends thereof.

The casing 36 is provided with an inlet 90

port 37, communicating with a discharge opening of the pump through a conduit 38 and supplying fluid pressure for actuating the operating piston of the relay. The casing is further provided with discharge ports 39 and 41, communicating with a conduit 42, which returns the discharged fluid to the reservoir 64. The casing is further provided with ports 43 and 44, communicating with the upper and lower ends, respectively, of a cylinder 45 in which is disposed an operating piston 46. The piston 46 is connected to and operates the valves of the steam chest 11 through any suitable means, such means being here shown as a rod 47.

A pilot valve 48 is disposed and operates within the cylindrical casing 36. The pilot valve is provided with piston portions 49 and 51 which normally cover the ports 43 and 44, respectively. Piston portions 52 and 53 are also provided at the ends of the pilot valve beyond the discharge ports 39 and 41, respectively. The pilot valve 48 is formed with a hollow interior and is closed at the upper end. A tension spring 54 is disposed within the hollow interior, having one end secured to the closed upper end of the pilot valve and having its other end secured to the upper end of a stem 55, which extends through the lower end of the casing. The stem 55 is connected at its lower end to a lever 56 intermediate the ends of the latter. The lever 56 is connected at one end to a stationary pivot 57, and at its other end is pivoted to the rod 47 as indicated at 58.

The drain conduit 42 also communicates with the chamber 19.

The operation of this embodiment of my invention is as follows:

The pump provides a governing fluid pressure which is transmitted to the lower end of the relay casing 36 and biases the pilot valve 48 upwardly against the force of the spring 54. The governing fluid pressure is also transmitted to the chamber 21 of the pressure transformer 16, and a small quantity thereof flows through the passage 25 and the restricted orifice 27 to the groove 29.

The upper end of the cylindrical casing 36, the conduit 34, the passage 33, the groove 29, and the recess 59 provide an enclosed space in which the fluid flowing to the groove 29 is received. The restricted flow of fluid into this space is controlled by adjustment of the needle valve 26, and builds up the pressure therein until the pressure in the recess 59 acting on the valve 24, together with the governing fluid pressure on the piston 23, overcomes the force of the spring 32, when the valve 24 lifts and permits escape of fluid from the enclosed space to the chamber 19.

Upon an increase in governing fluid pressure, the increased pressure acting on the piston 23 raises the valve 24 slightly, permitting fluid to escape from the enclosed

space until the pressure therein is reduced to offset the increased force exerted against the spring 32. Upon a decrease in governing fluid pressure, pressure on the piston 23 is reduced and the spring 32 moves the valve 24 to closed position until the pressure in the enclosed space builds up to again balance the spring 32 together with the pressure on the piston 23.

Upon an increase in speed of the prime mover the pressure developed by the pump increases, increasing the pressure acting on the lower end of the pilot valve 48 and decreasing the pressure acting downwardly on the upper end. The sum of these pressure changes moves the pilot valve 48 upwardly until the increased tension of the spring 54 equals the sum of the pressure changes. The port 43 is now in communication with the port 37, and fluid pressure is supplied to the upper end of the cylinder 45, moving the piston 46 downwardly to close the valves in the steam chest 11. The port 44 is placed in communication with the discharge port 41 and the fluid beneath the piston 46 is discharged to the inlet of the pump. As the valves close, the lever 56 moves downwardly, drawing the stem 55, the spring 54 and the pilot valve 48 down until the ports 43 and 44 are again closed by the piston portions 49 and 51.

Upon a decrease in speed the governing fluid pressure decreases, resulting in a decreased pressure acting on the lower end of the pilot valve and an increased pressure above the pilot valve. The pilot valve 48 moves downwardly until the spring tension is decreased by a force equal to the sum of the pressure changes. The port 44 is placed in communication with the pressure supply port 37 and the port 43 is placed in communication with the discharge port 39. The piston 46, therefore, moves upwardly to open the valves in the steam chest, and the lever 56 moves upwardly until the piston portions 49 and 51 again cover the ports 43 and 44.

The speed setting of the governor may be changed by turning the screw 63 to vary the force of the spring 32, and, therefore, the value of the fluid pressure in the enclosed space.

From the above description it will be apparent that I provide greater variations in the fluid pressure acting on the pilot valve 48, whereby adequate movements of the operating piston 46 may be obtained for a given change in speed. It will also be noted that by increasing the governing action on the pilot valve 48, a greater opening of the ports 43 and 44, and hence a more rapid operation of the steam chest valves, is obtained.

Referring particularly to the pressure transformer, it will be noted that it is of simple and reliable construction, having but one movable member and but one spring.

It is also pointed out that the variations in fluid pressure above the pilot valve may be greater than the variations in the governing fluid pressure, and that the ratio thereof is 5 determined by the inverse ratio of the areas in the pressure transformer on which the fluid pressures act. In the device shown on the drawing, for example, the area of the piston portion 23 is approximately twice the 10 area of the recess 59. Upon a given change in the governing fluid pressure acting upon the piston portion 23, therefore, there must be twice as great a variation in the fluid pressure in the recess 59 to offset the change in 15 force opposing the spring 32. It is thus possible, by a choice of said areas, to obtain any magnitude of pressure variation on the pilot valve 48 for a given change in speed.

In Fig. 2, I show a modified form of pressure transformer 16', in which the governing fluid pressure is admitted through a conduit 15' and an orifice 61, and applied to a central recessed area 23' of a relief valve 24'. A restricted flow of fluid passes from the conduit 25 15' through an orifice 27' to a conduit 34' and to an annular groove 29' in the casing 17', where its escape is controlled by the relief valve 24'. Fluid escaping from the recessed portion 23' and from the groove 29', is discharged to a drain conduit 42'.

The operation of the pressure transformer 16' is similar to that of the device shown in Fig. 1, a pressure varying inversely with the governing fluid pressure being transmitted 35 through the conduit 34'.

While I have shown my invention in several forms, it will be obvious to those skilled in the art that it is not so limited, but is susceptible of various other changes and 40 modifications, without departing from the spirit thereof, and I desire, therefore, that only such limitations shall be placed thereupon as are imposed by the prior art or as are specifically set forth in the appended claim.

45 What I claim is:

In a fluid-pressure governor for a prime mover having an admission valve, the combination of a pump developing a fluid pressure varying with its speed, means providing 50 an enclosed space, means providing a restricted flow of fluid under pressure into said enclosed space, means responsive to said fluid pressure for controlling the escape of fluid from said enclosed space and thereby controlling the pressure therein inversely to 55 the first-mentioned fluid pressure, valve operating mechanism for controlling the admission valve and including a pressure responsive element and a spring biasing the 60 element, said mechanism operating upon change in spring deflection to provide a valve movement proportional to the change in spring deflection, means for applying the first-mentioned fluid pressure to the pressure 65 responsive element in valve closing direction,

and means for applying the fluid pressure in said enclosed space to said element in opposition to the first-mentioned fluid pressure so that the variations in the former fluid pressure assist the variations in the latter fluid 70 pressure to provide increased spring deflection and consequent increased valve movement.

In testimony whereof, I have hereunto subscribed my name this 7th day of June, 1928. 75
